UNITED STATES PATENT OFFICE.

HARRY K. GROUT, OF MUSCATINE, IOWA.

DEVICE FOR MEASURING AND CUTTING FABRICS.

1,133,133.

Specification of Letters Patent. Patented Mar. 23, 1915.

Application filed January 23, 1914. Serial No. 813,930.

To all whom it may concern:

Be it known that I, HARRY K. GROUT, a citizen of the United States, residing at Muscatine, in the county of Muscatine and 5 State of Iowa, have invented a new and useful Device for Measuring and Cutting Fabrics, of which the following is a specification.

The invention relates to improvements in 10 devices for measuring and cutting ribbon, cloth and other fabrics.

The object of the present invention is to improve the construction of measuring and cutting devices, and to minimize the waste 15 resulting from cutting and measuring such material, and to provide a simple, inexpensive and efficient device of strong and durable construction, adapted to be readily mounted upon a counter or similar support, 20 and capable of being easily operated and of enabling cloth, ribbon and the like to be cut off squarely and with greater rapidity than can be done with hand scissors.

With these and other objects in view, the 25 invention consists in the construction and novel combination of parts hereinafter fully described, illustrated in the accompanying drawing, and pointed out in the claim hereto appended; it being understood that various 30 changes in the form, proportion, size and minor details of construction, within the scope of the claim, may be resorted to without departing from the spirit or sacrificing any of the advantages of the invention.

35 In the drawing: Figure 1 is a perspective view of a measuring and cutting device, constructed in accordance with this invention. Fig. 2 is a longitudinal sectional view of one end of the device. Fig. 3 is a detail sectional view on the line 3—3 of Fig. 2.

Like numerals of reference designate corresponding parts in all the figures of the drawing.

In the accompanying drawing in which is 45 illustrated the preferred embodiment of the invention, 1 designates an oblong table provided with legs or, supports 2 designed to be secured upon a counter 3, as illustrated in dotted lines in Fig. 1 of the drawing, but 50 it may be mounted in any other suitable manner, such as by brackets or legs of the proper length to rest upon the floor. The legs or supports 2 are shown in the drawing in the form of castings, but they may be of 55 any other desired construction. The table

1 is provided at intervals with raised transverse lines or edges 4, extending entirely across the table and adapted to be conveniently formed by metallic strips embedded in grooves or recesses 5, as clearly illustrated 60 in Fig. 2 of the drawing. These transverse lines or edges 4, which may be of any desired number, correspond with scale graduations 6 of a longitudinal guide 7 consisting of a bar or strip of metal secured to and extending along the front edge of the table and above the upper face thereof and above the projecting lines or edges 4, which correspond with the scale graduations of the straight edge or guide 7. The guide is preferably located at the front or outer edge of the table in order that the graduations may be visible to customers, and the raised lines or edges enable the said graduations to be readily located by touch so that a fabric or 75 ribbon may be accurately measured without seeing the graduations of the guide.

The table is equipped at one end with a movable cutter 8 pivoted to the table by a pin 9 or other suitable fastening device and 80 located at one end of the longitudinal guide 7 and consisting of an upper blade 10 and a lower arm 11 of substantially the same length as the blade 10. The blade 10, which is provided with a lower cutting edge, is of a 85 length to extend entirely across the table, and it cooperates with an upper cutting edge 12 of a stationary blade 13 fixed to the adjacent edge of the table by screws or other suitable fastening devices and extending entirely across the same. The stationary blade, 90 which has its side faces arranged in a vertical plane, is pierced by and forms a support for the pivot 9, and its upper edge is beveled at the inner side to provide an upper cutting edge.

The movable cutting blade 10 is normally supported in an elevated position above the top of the table in convenient position for instant use by a coiled spring 14, disposed 100 on a rod 15, which connects the lower arm 11 with a treadle 16. The coiled spring is interposed between a fixed screw eye 17 and the arm 11, and is adapted also to maintain the treadle normally in an elevated position, 105 as illustrated in Fig. 1 of the drawing, and when the treadle 16 is depressed to operate the movable cutter, the spring 14 is compressed and is adapted to elevate the treadle 110 and the movable cutter when the said treadle

is relieved of the pressure of the foot. The screw eye 17 through which the rod 15 passes has its threaded stem embedded in the end of the counter 3, but any other suitable means may be employed for supporting the lower end of the coiled spring 14. In operating the device the salesman or other person takes a bolt or bundle of fabric in one hand and grasps the free end of the same with the other hand and places the fabric upon the table, being careful to arrange the fabric against the straight edge or guide 7. This will enable the proper amount of material to be rapidly and accurately measured, and the measured portion may be instantly severed from the bolt or bundle by depressing the treadle, the movable cutter making a perfectly square cut and minimizing any loss or waste of material due to cutting.

While the cutting edge of the blade 10 is shown straight in the accompanying drawing, it may be curved longitudinally to present a convex cutting edge. This will increase the angle between the cutting edge of the blade 10 and the cutting edge of the coacting stationary blade and will enable an easier cutting of the material to be effected.

What is claimed is:—

A device for measuring and cutting fabrics comprising a table provided at intervals with transverse grooves, thin transverse strips seated in the grooves and projecting above the upper face of the table to form raised transverse edges which extend entirely across the table from the front edge to the rear edge of the same, a longitudinal guide plate secured to and extending along the rear edge of the table and projecting above the same and also above the said raised transverse edges to form a continuous guide for the material the full length of the table, said longitudinal plate being located at the rear ends of the raised edges and provided with scale graduations corresponding therewith, and cutting mechanism extending across one end of the table and arranged to sever the material as the same leaves the said guide plate.

In testimony, that I claim the foregoing as my own, I have hereto affixed my signature in the presence of two witnesses.

HARRY K. GROUT.
